Harold S. Mackay Inventor

By his Attorney
Wilkinson, Grinsta and Mackay

UNITED STATES PATENT OFFICE.

HAROLD S. MACKAYE, OF YONKERS, NEW YORK.

THERMALLY-CONTROLLED CONTAINER.

1,202,301.

Specification of Letters Patent.

Patented Oct. 24, 1916.

Application filed April 29, 1914. Serial No. 835,124.

To all whom it may concern:

Be it known that I, HAROLD S. MACKAYE, a citizen of the United States, residing at Yonkers, in the county of Westchester and 5 State of New York, have invented certain new and useful Improvements in Thermally-Controlled Containers; and I do hereby declare the following to be a full, clear, and exact description of the invention, such as 10 will enable others skilled in the art to which it appertains to make and use the same.

The present invention relates to an inexpensive and effective toy made preferably in the form of a self-hatching egg, capable of 15 repeated performance of the hatching process. This toy makes an effective table favor or Easter novelty. It is to be understood that the egg shape is not an essential feature of the invention.

20 Figure 1 of the accompanying drawings is a vertical sectional view of one form of the device, Fig. 2 is a top view of the form shown in Fig. 1, Fig. 3 is a sectional detail view of the catch, Fig. 4 is a perspective view of the sensitive bar as used in Figs. 1, 2 and 3, Fig. 5 is a sectional view of a modified form, having an internal bar, Fig. 6 is a perspective view of a substitute sensitive element, Fig. 7 is a sectional view of another modified form of egg-shaped box and Fig. 8 is an elevation of the box shown in Fig. 7.

25 The operation of my device depends upon the action of a sensitive strip which, when heated or cooled, as the case may be, bends so as to cause the opening or "hatching" of the egg.

30 Figure 1 shows a toy composed of an egg-shaped box in two parts 32 and 33, with a spring jumping jack 34 within it, which tends to throw open the lid. A bent spring locking bar 35 has beveled tips 36 which normally hold the lid in place by the ridges 37. Or they may enter a groove in the lid, 35 as shown in Fig. 3. This bar is the sensitive element, and in the form shown in Fig. 1 is made of two strips of different expansion coefficients, as shown in Figs. 3 and 4. When such a structure is heated (as by placing in 40 an oven or in a cup containing hot water) the spring bar opens and the lid is forced up. By reversing the component strips of the bar, in a well known manner, the same

will operate when cooled, as by setting on ice. The bar 35 may be set within the casing 55 as in Fig. 5, in which case its resilient tendency is outward.

In Fig. 6 is shown a modified sensitive element made of one bent metal strip 38, around which is stretched a taut string or 60 wire 39 of lower coefficient of expansion than the strip 38. This may be used as in Fig. 1, and will open when heated.

In Figs. 7 and 8 is shown a modification in which the sensitive strip 40 is set so as to 65 be movable within a slot 41 in the egg. When properly affected by changes in temperature, the tip of the member 40 will bend inward and push in the catch 42, whereby the lid is normally held down. The spring 70 43 will then open the egg.

Modifications may be made in the details herein shown and described without departing from the scope of my invention.

What I claim is—

1. A self-opening box, in combination with a sensitive strip adapted to change its form when subjected to a change in temperature, and locking means for the box operatively connected with said strip, whereby a change 80 in form of said strip will unlock the box, substantially as described.

2. A self-opening box, in combination with a resilient strip adapted normally to hold the box closed by its resilience, said 85 strip being composed of parts having different coefficients of expansion so placed as to overcome said resilience when subjected to an appropriate temperature change, substantially as described.

3. A self-hatching Easter egg comprising two separable portions, means normally tending to separate said portions, means for holding said portions together, and a member sensitive to temperature changes adapted 95 to move said locking means to permit said portions to separate, substantially as described.

4. A self-hatching Easter egg comprising two separable portions an element sensitive 100 to temperature changes carried by one portion, and means on said element adapted to engage and lock the other portions, substantially as described.

5. A self-hatching Easter egg comprising 105 two separable portions, a bow-shaped strip

sensitive to temperature changes conforming to the contour of one of said portions and means on said strip adapted to engage and lock the other portion, substantially as described.

6. A self-hatching Easter egg comprising two separable portions, a spring tending to separate them and a lock for holding them together consisting of a strip sensitive to

temperature changes, substantially as de- 10 scribed.

In testimony whereof, I affix my signature, in presence of two witnesses.

HAROLD S. MACKAYE.

Witnesses:
